U.S. PATENT DOCUMENTS

The ornamental design for a firearm suppressor, as shown and described.

DESCRIPTION

4,588,043 A	5/1986	Finn
6,308,609 B1	10/2001	Davies
6,374,718 B1	4/2002	Rescigno et al.
6,575,074 B1	6/2003	Gaddini
7,308,967 B1	12/2007	Hoel
8,087,338 B1	1/2012	Hines
8,096,222 B2	1/2012	Silvers
8,100,224 B1	1/2012	Olson
8,307,946 B1	11/2012	Johnston
8,474,361 B2	7/2013	Brittingham
8,505,431 B2	8/2013	Hines
8,807,272 B2	8/2014	Bladen
8,991,550 B2	3/2015	Coley

FIG. 1 is a front, top, left side perspective view of a firearm suppressor according to the present disclosure.

FIG. 2 is a rear, top, right side perspective view of the firearm suppressor of FIG. 1.

FIG. 3 is an enlarged front view of the firearm suppressor of FIG. 1.

FIG. 4 is an enlarged rear view of the firearm suppressor of FIG. 1; and,

FIG. 5 is a right side view of the firearm suppressor of FIG. 1.

The broken lines in the Figures and the unshaded areas within the broken lines illustrate portions of the firearm suppressor that form no part of the claimed design.
